UNITED STATES PATENT OFFICE.

ASHLEY G. OGDEN, OF BALTIMORE, MARYLAND, ASSIGNOR TO AMERICAN MACHINE & FOUNDRY COMPANY, A CORPORATION OF NEW JERSEY.

PHOTOGRAPHIC-PRINTING DEVICE.

Application filed March 5, 1921. Serial No. 449,801.

To all whom it may concern:

Be it known that I, ASHLEY G. OGDEN, a citizen of the United States, and a resident of Baltimore, county of Baltimore, and 5 State of Maryland, have invented certain new and useful Improvements in Photographic-Printing Devices, of which the following is a specification.

This invention relates to photographic printing devices and is herein disclosed as applied to a multiple printing device adapted to produce plates for lithographic printing. One form of such a device is shown in my Reissue Patent No. 14,517, dated September 3, 1918. Such plates are largely used in the art of lithography, especially for printing upon tin when it is desired from a single negative to produce a number 10 of plates which shall be identical and shall be accurately registered with each other and with other plates which may be used for printing several colors upon the same cans or other printing surfaces. In order to obtain the accurate registry in producing such 15 plates, the photographic printing devices employed are massive in construction and for purposes of economy in printing, they are often built large enough to accommodate a very large plate with the result that the 20 handling of the negative and the sensitized surface are a problem involving many factors.

In the devices to which the present invention is herein shown as applied, the sensitized plate is carried by a shiftable cradle or carrier over a table in which the negative is mounted, and mechanical devices of great accuracy in construction are usually employed to accurately center the sensitized 25 surface at a number of positions above the negative which is usually mounted in the body of the table. In making the exposures upon a sensitized surface to produce the desired plate, the surface is shifted across the 30 table so that light coming from below up through the negative will make the desired exposure upon the plate. This shifting of the sensitized plate involves lifting it or its supports clear of the surface of the table, then shifting the sensitized surface carrier to the new position, with the result that unless aprons or other light intercepting devices are provided the sensitized surface 35 may become light-struck.

According to the present invention instead

of employing an apron or other device which has to be separately handled, or which is likely to interfere with the smooth operation of the mechanism, the surface of the table may be provided with a resilient 40 covering such as a pile fabric, preferably black, which tends to absorb light and which springs up slightly when the plate-carrier is lifted to the slight extent required to shift it to a new printing position. 45 The carrier itself may also be provided with a similar surface preferably of black pile fabric, thus absorbing any light which might otherwise get between the bottom of the carrier and the top of the pile fab- 50 ric upon the table. It has been found that two opposed surfaces of pile fabric like plush, utilized in this way, make a very effective barrier for the light which otherwise might fog the sensitized surface. The re- 55 silency of the pile fabric makes it particu- 60 larly effective in devices like the one disclosed in which the plate carrier has an up and down motion when shifted transverse- 65 ly for printing each exposure. Other fea- 70 tures and advantages will hereinafter ap- 75 pear.

In the accompanying drawings,

Figure 1 is a perspective view of a device of a general type shown in said reissue patent and embodying the present invention.

Figure 2 is a sectional side view of a detail showing the cradle on a larger scale.

Figure 3 is a bottom perspective view of part of the cradle and the frame therein showing the plush surfaces thereon.

The table 1 is usually of extremely massive construction having integral thereon a V-shaped rail 2 and a flat rail 3 upon which slides a main or primary carriage 4. The plate or sensitized surface 5 is carried in a plate-holder 6 which is supported upon the lugs 7 in a holding device in the form of a frame 8 seated in a cradle having sides 8^a and which forms part of a secondary carriage 9 slidable upon the main carriage 4. For the purpose of obtaining great accuracy in the operation of the mechanism the secondary carriage 9 runs upon a V-shaped rail 10 and a flat rail 11 on the main carriage and is slidable therealong by a screw-drive shaft 12 like the screw-drive shaft 13 which serves to drive the main carriage on its rails 2 and 3. The cradle 8^a therefore shifts the sensitized surface 5 110

2
across the flat top 21 of the table 1 according as it is moved by the main carriage 4 or the secondary carriage 9, or by both carriages.

5 The cradle and frame 8 are adapted to be raised and lowered in the secondary carriage 9 by links 14 which are connected to rock arms 15 fast upon shafts 16 connected by a link 17 to be operated by a
10 handle 18. The sensitized surface 5 is adapted to be pressed against a negative 18^a (see Fig. 2) supported in an opening 19^a in the table 1 by a pressure head 19 against the tension of springs 20 which normally
15 lift it clear of the negative. In ordinary use the desired print is made upon the sensitized surface by a lamp, not shown, beneath the table 1, the latter serving as a
20 shield to prevent access of light to the sensitized surface except through the negative mounted in the table or shield. In order to prevent the entry of any light to the sensitized surface 5 by leakage under the frame 8 and across the top 21 of the table
25 1, the table top 21 is provided with a cover adapted to intercept the light and yieldable, yet resilient enough to rise after being depressed. For this purpose the table top 21 is usually covered with a resilient fabric
30 such as black plush having a fairly long pile, and held down to the table top in any suitable manner. The pile fabric is preferably applied in fairly wide breadths, so that there are only a few joints 22 where the
35 fabric is joined, thus minimizing the likelihood of light leakage along the joints and minimizing the liability of the fabric to be caught up by the transversely moving cradle 8^a or frame 8.
40 The fabric is diagrammatically illustrated at 23 in Figure 2, and as herein shown, there is also a corresponding layer of pile fabric 24 upon the lower faces of the cradle 8^a and the frame 8. The cradle and
45 frame 8 may be only a few inches wide, but it is found that even with a narrow cradle and frame 8, narrow widths of fabric 24 co-operating with a fabric 23 upon the table surface 21 are sufficient to prevent fogging
50 by outside light of even a high speed glass plate, if such is used as the sensitized surface 5. Where a slower working sensitized surface is used one fabric face, as the pile fabric 24, may be sometimes omitted. It
55 has been found that a suitable black plush has a sufficiently long pile to enable the cradle 8^a to be safely shifted a large number of times in printing upon a glass plate at 5, without the need of interposing the shield
60 which has sometimes been used to cover the sensitized surface in the plate-holder to prevent it from being light-struck and which runs in slides 25.

65 This device therefore, enables rapid printing to be made upon a glass plate of a

number of images or prints from a single small negative. The present device is therefore, used for the rapid preparation of lithographic plates by printing from a single small negative a considerable number 70 of reproductions thereof upon a fairly large rapid glass plate, and then making the slow printing zinc or other lithographic printing plate in a few long exposures from the glass plate thus prepared. Working in this way with the mechanism here disclosed, it has been found possible to accomplish the work of printing the final zinc or other plate in a fraction of an hour, instead of occupying 75 perhaps a day as has hitherto been the case. 80

In order to facilitate the rapid use of the mechanism, the usual slidable section 26 of the table 1 is provided and is covered with the pile fabric 23. This section is easily removable by sliding it out horizontally to enable the plate-holder and its support to be removed by sliding out horizontally in the usual manner. It is found that the device works satisfactorily in excluding light even if brass strips 27 are used for the purpose of preventing their wear at the margins where the pile fabrics slide past each other. 85

90 In order to facilitate the utilization of the mechanism for either the thickness of plate-holder used for glass plates, or for other thicknesses of plate-holders, or where it is desired to interpose a body 28 between the pressure head 19 and the back of the plate-holder 6, the handle 29 for operating the pressure head may have a device whereby it is automatically locked in position at any tension desired by the operator irrespective of the position of the pressure head. 95 For this purpose the pressure head is operated in the usual manner by links 30 connected to an integral pair of rock arms 31, which in turn are fast to a rock arm 32 connected by a link 33 to a rock arm 34 fast to the handle 29. The arrangement of parts is such that the handle 29 is slightly overthrown in pressing down the pressure head 19 and is arrested by a stop 35 when so overthrown, thus in effect forming a toggle joint for exerting pressure through the pressure head 19. 100

105 In order to vary the length of the link 33 to enable this to be accomplished under various circumstances, the link 33 is formed in two parts connected by a screw turn-buckle 36 which the operator soon learns to adjust rapidly to adjust the length of link to suit the particular conditions of each exposure. 110

115 The crack 37 around the edges of the plate support is usually covered with some light-excluding material, omitted herein for clearness in showing the underlying structure. 120

125 Having thus described one embodiment 130 of my invention, what I claim is:

1. In a photographic printing device, the combination with a shield having an opening for a negative, of a sensitized surface holding device adapted to be shifted to a plurality of printing positions across said shield to be exposed to the negative, a black pile surface on the shield, and a black pile surface on the holding device adapted to lie against the first pile surface to form a light-tight joint around the sensitized surface.
2. In a photographic printing device, the combination with a shield having an opening for a negative, of a sensitized surface holding device adjacent the shield, means for shifting a device across the shield to bring different portions of the sensitized surface to the negative, means for effecting separation between the shield and device to separate the sensitized surface from the negative, and a fabric having a resilient pile and lying upon the shield to prevent light from entering between the supporting device and the shield.
3. In a photographic printing device, the combination with a table forming a shield, of a main carriage shiftable transversely of the shield, a secondary carriage shiftable transversely on the main carriage, a cradle for supporting a sensitized surface and carried by the secondary carriage, a resilient light-excluding surface at the back of the cradle, with a resilient pile fabric surface upon the shield to co-operate with the frame surface to exclude light.
4. In a photographic printing device, the combination with a shield forming negative support, of a plate-holder adapted to carry a sensitized surface, a resilient device normally holding the sensitized surface clear of the negative, a pressure device for pressing the surface to the negative, a cradle carrying the plate-holder, a pile fabric facing on said plate-holder and a pile fabric facing on the shield so that the two pile fabrics form a light-excluding device.
5. In a photographic printing device the combination with a shield forming negative support, of a plate-holder adapted to carry a sensitized surface, a resilient device normally holding the sensitized surface clear of the negative, a pressure device for pressing the surface to the negative, a cradle carrying the plate-holder, a pile fabric facing on said plate-holder, a pile fabric facing on the shield so that the two pile fabrics form a light-excluding device, a main carriage for shifting the cradle across the shield, a secondary carriage for carrying the cradle across the main carriage, and means for lifting the cradle in the secondary carriage.
6. In a photographic printing device the combination with a table forming a shield adapted to support a negative, of a cradle adapted to support a plate-holder carrying a sensitized surface, a main carriage shiftable across the shield, a secondary carriage shiftable across the main carriage and transversely thereof, and resilient light-excluding surfaces upon the cradle and the shield adapted to exclude light from the sensitized surface.
7. In a photographic printing device, the combination with a table forming a shield adapted to support a negative, of a cradle adapted to support a plate-holder carrying a sensitized surface, a main carriage shiftable across the shield, a secondary carriage shiftable across the main carriage and transversely thereof, resilient light-excluding surfaces upon the cradle and the shield adapted to exclude light from the sensitized surface, resilient means normally holding the sensitized surface clear of the negative in the cradle, and means for lifting the cradle from the shield sufficiently to facilitate transverse shifting of the cradle upon the shield.
8. In a photographic printing device, the combination with a support adapted to support a negative, of a holder adapted to normally support a sensitized surface clear of the negative and means for effecting movement of the surface and the negative, relatively toward and away from each other, and yieldable material so extending between the support and holder as to exclude light from the sensitized surface.
9. In a photographic printing device, the combination with a shield forming a negative support adapted to support a negative, of a holding device adapted to normally hold a sensitized surface clear of the negative, means for effecting movement of the surface and the negative relatively toward and away from each other, and yieldable material so carried by the support and holding device as to exclude light from the sensitizing surface.
10. In a photographic printing device, supports adapted to support a negative and a sensitized plate respectively, said supports having plane cooperative surfaces whereby one may be moved over the other, and a covering of long pile resilient fabric disposed between the two supports and adapted to exclude light from the sensitized plate.
11. The combination in a photographic printing device, supports adapted to support a negative and sensitized plate respectively, said supports having plane cooperative surfaces whereby one may be moved over the other, and a covering of pile fabric secured to said surfaces intermediate said supports and adapted to exclude light from the sensitized plate.
12. In a photographic printing device, the combination with a support adapted to support a negative, of a holder adapted to nor-

5 mally support a sensitized surface clear of the negative, means for effecting movement of the surface and the negative relatively toward and away from each other, and yield-
able material so arranged around the sensitized surface and extending between the support and holder as to exclude light from the sensitized surface.

10 13. In a photographic printing device, the combination with a support adapted to support a negative, of a holder adapted to normally hold a sensitized surface clear of the negative means for effecting movement of the surface and the negative, relatively toward and away from each other, and yield-
able material so surrounding the negative and sensitized surface and extending between the support and holder as to exclude light from the sensitized surface.

15 20 14. In a photographic printing device,

25 supports adapted to support a negative and a sensitized plate respectively, said supports having plane cooperative surfaces whereby one may be moved over the other, and yieldable material extending between said supports to exclude light from said sensitized plate.

30 15. In a photographic printing device, supports adapted to support a negative and a sensitized surface respectively, said supports having plane cooperative surfaces whereby one may be moved over the other, and yieldable resilient material so extending between said supports as to surround said negative and sensitized surface for the purpose of excluding light therefrom.

35 In testimony whereof, I have affixed my signature to this specification.

ASHLEY G. OGDEN
